UNITED STATES PATENT OFFICE.

EDWARD EUGENE BROWN AND DERMOT JOSEPH MOONEY, OF LONDON, ENGLAND.

METAL CONSTRUCTION.

1,360,720.

Specification of Letters Patent. Patented Nov. 30, 1920.

Application filed December 24, 1919. Serial No. 347,251.

To all whom it may concern:

Be it known that we, EDWARD E. BROWN and DERMOT J. MOONEY, both subjects of the King of England, and residents of London, 5 England, have invented a new and Improved Metal Construction, of which the following is a full, clear, and exact description.

This invention relates to improvements 10 in metal constructions, and more particularly to an improved construction of spar, an object of the invention being to provide a metal bar structure which combines strength with lightness of weight, and 15 which is especially adapted for use as a spar in wings, fuselages, struts, and the like in the construction of aeroplanes.

With these and other objects in view the invention consists in certain novel features 20 of construction, and combinations and arrangements of parts, as will be more fully hereinafter described and pointed out in the claims.

In the accompanying drawings—

25 Figure 1 is a fragmentary perspective view illustrating one form of our improved structure; and

Figs. 2, 3, 4, 5, 6, 7 and 8 are similar views illustrating modifications.

30 It will be noted that in all forms of our invention the bar is composed of plates 1 and 2 constituting the web of the bar, and these plates 1 and 2 at their edges are secured to plates 3 and 4 respectively. The 35 plates 1 and 2 are connected at their intermediate portions and this connected relatively narrow juncture of the two plates extends throughout the length of the bar, and these joined portions of the plates 1 and 2 40 are given reference numeral 5. The plates are secured together by riveting, spot welding, or any other means which will properly perform the function.

Above and below the connected portions 45 of the plates 1 and 2, the plates flare outwardly or apart and these flared portions may be on straight lines as indicated in Fig. 1, or it may be angular as indicated in Fig. 2, or it may be curved as indicated in 50 Figs. 3, 4, 5, 6 and 7. The upper and lower portions of the plates 1 and 2 project outwardly and are curved inwardly, as shown at

6, and the plates 3 and 4 have their edges 7 curved inwardly inclosing the curved portion 6 of the plates 2. The plates 3 and 4 55 are also preferably longitudinally corrugated, as shown at 8, to give the necessary strength.

As illustrated in Figs. 4, 5, 6 and 7 vertical stiffening blocks 9 may be employed 60 between the flanges of the bar and secured to the bar in any approved manner.

In Fig. 8, we illustrate a modification in which the plates 1 and 2 have the general angular contour as shown in Fig. 2, with the 65 addition of longitudinal beads or webs 10 formed thereon.

With all forms of our invention it will be noted that the edges of the upper and lower plates 3 and 4 are curved inwardly forming 70 lips which inclose the extreme edges of the plates 1 and 2 and hence, the four plates constituting the bar are all securely tied together and sustain each other when stresses or strains are put upon the bar from any 75 direction.

While we have illustrated no particular means for securing the plates 1 and 2 to the plates 3 and 4, it is, of course, to be understood that these plates can be rigidly connected 80 in any manner well known in the art.

It is, of course, to be understood that several plates forming the bar are preferably of relatively thin sheet steel so as to embody the maximum of strength and durability with the least possible weight, but it is also possible that other materials than steel may be employed and other slight modifications in shape might be resorted to without departing from our invention. We 90 therefore do not wish to be limited to the precise details set forth, but consider ourselves at liberty to make such changes and alterations as fairly fall within the spirit and scope of the appended claims. 95

We claim:

1. A bar of the character described, comprising a pair of plates having their intermediate portions secured together and flared apart at opposite sides of their point of connection, said plates having their edges projected outwardly and curved inwardly at their free edges, and plates positioned over said outwardly bent portions of the first-

mentioned plates and having their edges bent inwardly confining the edges of the first-mentioned plates.

2. A bar of the character described, comprising a pair of plates forming the web of the bar, said plates secured together at their intermediate portions and flared apart above and below their points of connection, out-

wardly projecting flanges at the edges of the plates, and other plates located at the ends of the webs and positioned against the flanges, said flanges and last-mentioned plates having inwardly curved edges. 10

EDWARD EUGENE BROWN.
DERMOT JOSEPH MOONEY.
